attorney

UNITED STATES PATENT OFFICE

SAMUEL T. HENSEL, OF DENVER, COLORADO

SIRUP PERCOLATOR

Application filed July 5, 1929. Serial No. 376,253.

This invention relates to improvements in percolators for making simple sugar sirups such as are used with soda water fountains and has reference more particularly to an improvement over the structures described and claimed in the following Letters Patent of the United States heretofore granted to me, to-wit: Patent No. 912,959, February 16, 1909, and Patent No. 939,131, November 2, 1909.

In the preparation of soft drinks, such as are sold in drugstores and which are dispensed by means of the ordinary soda water fountains, it is customary to mix the flavoring with a saturated sugar syrup to which the carbonated water is added in a certain proportion.

It is the object of this invention to produce a simple device which can be employed for the production of the sirup and which shall be so constructed and the parts so proportioned that it will produce a saturated sugar syrup suitable for the use above indicated.

In the patents above identified, similar devices have been shown and described. It has been found that devices constructed in accordance with the above identified patents are objectionable for the reason that the sugar which is contained in the annular chamber which surrounds the water receptacle does not freely feed because the thickness of the space between the wall of the sugar container and the water receptacle decreases towards the bottom.

It is the object of this invention to produce a percolator of the type referred to which shall be so constructed that the space in which the sugar is contained is of a uniform thickness from the upper end to the lower end thereof wherefore the sugar will freely feed and produce a sirup of uniform saturation.

The above and other objects which may become apparent as the description proceeds are attained by means of a construction and an arrangement of parts that will now be described in detail, reference for this purpose will now be had to the accompanying drawings in which the preferred embodiment of the invention has been illustrated and in which:

Fig. 1 is a vertical diametrical section through my improved percolator;

Fig. 2 is a section taken on line 2—2, Fig. 1; and

Fig. 3 is a section taken on line 3—3, Fig. 1.

My improved device consists of a cylindrical tank 1 having a bottom 2 which is located a short distance above the lower end of the cylindrical member which is flanged upwardly as indicated by reference numeral 3. The tank is provided with several circular corrugations 4 that serve to strengthen it and also gives it an ornamental appearance. The upper end of the tank is bent downwardly in the manner indicated at 5. Secured to the tank directly above the bottom 2 is a faucet 6 by means of which the sirup can be withdrawn from the tank. Located within the tank is a container 7. This container is made in the form of the frustum of a cone. The diameter of the larger base is substantially equal to the inside diameter of the tank and the edge of the container is rolled in the manner indicated at 8. This roll rests on the upper end of the tank and serves to support the container within the latter. The smaller diameter of the container is less than the inside diameter of the tank and is closed by a plate 9 which forms the bottom thereof. The wall of the container is provided with a plurality of perforations 10 which are located a short distance above the bottom. A screen 12 covers the openings 11 in the manner shown. A strap 13 having parallel spaced outwardly extending lugs 14 encircles the lower end of the container and is held in place thereon by the clamping action produced by the bolt 15 that passes through openings in lugs 14. By moving the strap 13 upwardly from the position shown in Fig. 1, the effective areas of openings 11 can be varied, so that by this simple expedient a convenient adjustment is afforded.

Secured to the upper surface of base 9 are plates 16 that have their outer edges soldered to the base 9 and have their inner edges raised a short distance above the base for a purpose which will hereinafter more fully appear. Located within the container 7 is a receptacle 17.

This receptacle is also made in the shape of a frustum of a cone and is slightly shorter than container 7 and is supported by means of a U-shaped support 18 secured to the bottom 19 which closes the smaller end of the receptacle. The support 18 has outwardly extending feet 20 that are adapted to slide into the spaces between the upper surface of bottom 9 and the lower surfaces of plates 16. The support 18 is so adjusted that it will hold the receptacle 17 in concentric relation within the container 7. The inclination of the walls of the container and receptacle with the common axis is the same and therefore the walls are concentric in every horizontal plane. The lower end of the receptacle 17 is also provided with openings which have been indicated by reference numeral 21. These openings are screened in the manner shown. A cover 22 is provided with a downwardly extending cylindrical flange 23 that fits into the upper end of the container. This cover has an outwardly extending flange 24 that extends over the rolled end of the container and serves as a support for the cover. The cover is provided with a knob 25 by means of which it can be readily removed and replaced. The container and receptacle are so proportioned that the cubical contents of the receptacle is one-third the cubical contents of the container and therefore the chamber between the two has a capacity equal to twice that of the receptacle. When the percolator is employed for making syrup sugar is put into the space between the walls of the container and the receptacle and this sugar has been designated by reference numeral 26. The receptacle is then filled with water which has been designated by reference numeral 27. The water from the receptacle flows outwardly through openings 21 and mixes with the sugar which dissolves and forms a concentrated sugar syrup in which the water is completely saturated with sugar. This syrup flows outwardly through openings 11 into the tank. The proportions of sugar and water necessary to form a saturated solution is practically two volumes of sugar to one of water and the space for the sugar and the space provided for the water are so proportioned that their volumes are such as to form a concentrated syrup. It is therefore only necessary to fill the sugar container with sugar and the water receptacle with water in order to form a syrup of the desired concentration.

I have previously pointed out that with the structures shown in my patents a slight difficulty was experienced due to the fact that the sugar could not move freely downwardly in the space between the receptacle and the container and therefore it sometimes happened that the syrup would vary in its concentration. With the construction shown and described above, the distance from the

outer wall of the receptacle to the inner wall of the container is equal at all points from the bottom to the top and therefore the sugar can freely flow downwardly to replace that which is dissolved, and which has passed into the tank in solution. 70

In the present embodiment the container and the receptacle have been shown as provided with conical walls which taper downwardly and therefore it is evident that the area of the space that contains the sugar diminishes towards the bottom, but since the taper can be made very small, this variation is not sufficient to produce any undesirable retardation of the feeding of the sugar. If the taper of the container and receptacle is gradually reduced until they approach the shape of a cylinder, there will, of course, be no crowding action when the sugar moves downwardly. 75

I want to call particular attention to the specific construction which I am employing and by which I obtain a chamber for the sugar whose walls are parallel from the top to the bottom and which therefore permits the sugar to move down freely so as to continually replace that which has been dissolved by the water. I also want to call attention to the fact that the nearer the container and receptacle are to a cylinder, the more completely will the object of my invention be attained. The conical shape employed has been used in preference to a cylindrical shape because it presents several advantages in construction. 80 85 90 95

Having described my invention what is claimed as new is:

1. A simple syrup percolator, comprising a sugar container whose body portion is frusto-conical in shape and provided at the end having the smaller diameter with an imperforate bottom, the wall of the container having a plurality of perforations a short distance above the bottom, said perforations being covered with wire screens of suitable mesh, the upper surface of the bottom having secured to it two anchoring plates (16) symmetrically located on opposite sides of a diameter, the adjacent edges of the plates being spaced from the bottom, a frusto-conical water container located within the sugar container, the two containers having the same taper, the water container having an imperforate bottom and having its wall provided with openings directly above the bottom, the openings being covered with a suitable screen, the bottom of the water container having a U-shaped support whose lower ends have outwardly extending feet adapted to engage the spaces between the plates and the bottom and to serve to hold the water container in position. 100 110 115 120

2. A syrup percolator, comprising a sugar container having an imperforate bottom and a conical upwardly and outwardly inclined 125 130

side wall, the wall directly above the bottom having a row of perforations, a water receptacle located within the sugar container, the sugar container and the water receptacle having the same shape and concentrically located whereby the radial distance between the outer wall of the water container and the inside wall of the sugar container is equal in all spaced planes perpendicular to the common axis of the sugar container and water receptacle, the lower end of the wall of the water receptacle having a row of perforations closed by strainer material, the water receptacle being otherwise imperforate, and means for securing the water receptacle to the sugar container.

In testimony whereof I affix my signature.
SAMUEL T. HENSEL.
